UNITED STATES PATENT OFFICE.

JAMES W. EMBREE, OF MANHATTAN, KANSAS.

TRUSS-PAD.

1,273,755.

Specification of Letters Patent. Patented July 23, 1918.

Application filed November 14, 1917. Serial No. 201,937.

To all whom it may concern:

Be it known that I, JAMES W. EMBREE, a citizen of the United States, residing at Manhattan, in the county of Riley and State 5 of Kansas, have invented new and useful Improvements in Truss-Pads, of which the following is a specification.

My present invention pertains to truss pads.

10 One of the objects of the invention is the provision of a light body, susceptible of being easily and cheaply manufactured of aluminum or other suitable metal or alloy, and constructed with a view of strongly 15 holding and reinforcing a pad of plaster of Paris or analogous material.

Another object is to provide a pad body provided with improved means for strongly and comfortably mounting it on the body 20 strap, of webbing or other suitable material, and adjustably connecting it to the leg strap which is preferably of the same material as the body strap.

With the foregoing in mind, the invention 25 in all of its details will be fully understood from the following description and claim when the same are read in connection with the drawings accompanying and forming part of this specification, in which:

30 Figure 1 is a perspective illustrative of my improved truss construction complete, portions of the body strap and leg strap being broken away.

Fig. 2 is a face view of the pad, showing 35 the body also.

Fig. 3 is a face view or interior view of the pad body *per se*.

Fig. 4 is a vertical-central section, taken 40 through pad and body in the plane indicated by the line 4—4 of Fig. 2.

Fig. 5 is a transverse section of the pad body *per se*.

Similar numerals of reference designate 45 corresponding parts in all of the views of the drawings.

The pad 5 is formed of plaster of Paris or other suitable plastic material, and is preferably, though not necessarily, of the type disclosed in my contemporary applica- 50 tion, filed March 1, 1917, Serial Number 151,764—*i. e.*, is provided on the lower portion of its face with a curvilinear protuberance 6, and has formed in its face, above said protuberance 6, grooves or channels 7.

55 My present invention contemplates molding the said plastic pad or pad member in

a body 1 which is preferably of aluminum, for the sake of lightness, though it may be of any other suitable metal or alloy without affecting my invention. The said body 1 is 60 provided with a marginal flange 2 to inclose and protect the pad 5, and is also provided with the loop 4 and the curvilinear cross- rods 3, the latter being embedded in and calculated to reinforce the pad 5 as well as 65 strongly hold the same in the body and against the back and within the flange 2 thereof. It will be noted by reference to Fig. 5 that the ends of the curvilinear rods 3 are fixed in the corners between the flange 2 70 and the major portion of the body 1, and that by reason of the curvature of the rods in a direction away from the major portion of the body 1, the rods are enabled to engage a greater portion of and more strongly hold 75 the pad than would otherwise be the case. It will also be observed by comparison of Figs. 1 and 4 that the body 1 is provided on the upper portion of its back with brackets 8 between which is pivotally mounted a dog 80 9 having a plurality of teeth 10 at its free edge. The loop 4 is designed to straddle the body strap 12 which is interposed between it and the major portion of body 1, as shown, in Fig. 1, and the dog 9 is adapted to engage the leg strap 13 which is preferably 85 looped over it in the manner also shown in Fig. 1. By virtue of this latter arrangement, it will be noticed that any tendency of the major portion of the strap 13 to draw 90 downwardly, will have the effect of rendering more positive the engagement between the toothed edge of the dog and the strap, with the result that casual loosening or unfastening of the strap 13 is practically pre- 95 cluded. It will also be noticed that any downward pull on the major portion of the strap 13 will be exerted on the upper end portion of the pad, as is desirable.

In addition to the advantages hereinbefore ascribed, to my novel truss pad, it will be noticed that the same is light in weight and simple and inexpensive in construction, and that it embodies no delicate parts such as are liable to get out of order after a short 100 period of use.

Having described my invention, what I claim and desire to secure by Letters-Patent, is:

A truss pad comprising a metallic body 110 having a marginal flange and cross-bars curved in a direction away from the major

portion of the body and extending between the corners formed by said major portion and flange and also having a loop on its back, at its center, and spaced brackets on its back, adjacent to its upper end and above said loop, a dog pivotally mounted between the brackets and movable vertically, and a pad member of plastic material disposed within the flange and against the major por-

tion of the body and receiving the curvi- 10
linear cross bars of the body.

In testimony whereof I have hereunto set my hand in presence of two subscribing witnesses.

JAMES W. EMBREE.
